DESIGN FOR A BOTTLE OR SIMILAR ARTICLE

Meredith Stewart Ireys, Lancaster, Pa., assignor to Armstrong Cork Company, Lancaster, Pa., a corporation of Pennsylvania

Application March 13, 1940, Serial No. 90,884

Term of patent 14 years

To all whom it may concern:

Be it known that I, Meredith Stewart Ireys, a citizen of the United States, residing in Lancaster, county of Lancaster, and Commonwealth of Pennsylvania, have invented a new, original, and ornamental Design for a Bottle or Similar Article, of which the following is a specification, reference being had to the accompanying drawing, forming a part thereof, and of which—

Figure 1 is a view in elevation of the front of the bottle or similar article showing my new design;

The dominant features of my design reside in the portion shown in solid lines.

I claim:

The ornamental design for a bottle or similar article, substantially as shown and described.

MEREDITH STEWART IREYS.
